US00D892491S

(12) **United States Design Patent** (10) **Patent No.:** **US D892,491 S**
Feng (45) **Date of Patent:** **** Aug. 11, 2020**

(54) **BINDING DEVICE FOR ELECTRONICS**

(71) Applicant: **Guangzhou Landscape Communication Equipment Co., Ltd.**
 Guangzhou (CN)

(72) Inventor: **Youqing Feng**, Anqing (CN)

(**) Term: **15 Years**

(21) Appl. No.: **29/719,196**

(22) Filed: **Jan. 2, 2020**

(51) **LOC (12) Cl.** **03-01**

(52) **U.S. Cl.**

USPC **D3/201**; D14/250

(58) **Field of Classification Search**

USPC D14/250-253, 432, 434, 440, 447;
 D3/201, 318

CPC A45C 11/00; A45F 5/00; F16M 11/06

(57) **CLAIM**

The ornamental design for a binding device for electronics, as shown and described.

DESCRIPTION

FIG. 1 is a first perspective view of a binding device for electronics showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
